M. NAGLE

DYEING MACHINE

Filed Dec. 18, 1923

Fig. 4.
INVENTOR
Matilda Nagle,
BY C. P. Goepel
ATTORNEY

UNITED STATES PATENT OFFICE.

MATILDA NAGLE, OF BROOKLYN, NEW YORK.

DYEING MACHINE.

Application filed December 18, 1923. Serial No. 681,816.

To all whom it may concern:

Be it known that I, MATILDA NAGLE, a citizen of the United States, and a resident of Brooklyn, county of Kings, and State of New York, have invented certain new and useful Improvements in Dyeing Machines, of which the following is a specification.

This invention relates to dyeing machines and has for its primary object to provide an efficient and simply constructed machine for dyeing skeins of silk, yarn and other textile materials, and to this end embodies certain improvements in the machine shown and described in Patent No. 1,293,514, issued to me

15 on February 4, 1919.

More particularly, it is the object and purpose of my present improvements to provide a skein dyeing machine which is provided with means for automatically imparting to a plurality of skeins a bodily to-and-fro movement in the dye bath as well as a simultaneous spreading or separating movement between the parallel portions of the individual skeins, thus corresponding closely 25 to the usual manual or hand operation heretofore employed in the art.

In one embodiment of my present invention, I provide one or more transverse shafts 30 removably supported for longitudinal travel over the dye vat and each shaft having one or more skein receiving drums of elongated form fixed thereon. By means of suitable mechanism, a unitary reciprocating motion is imparted to the series of shafts, and in 35 the initial movement of these shafts in one direction the individual shafts are automatically given an axial rotating movement so that the elongated drums are partially turned about the shaft axes, thus expanding 40 or separating the parallel portions of the individual skeins which depend from the respective drums into the dye bath contained in the vat.

In this manner it will be seen that the 45 skeins are moved to and fro in the dye bath and the parallel strands thereof simultaneously spread apart or separated so that the bath material will thoroughly permeate the skeins, thus insuring the uniform dyeing 50 thereof.

With the above and other objects in view, the invention consists in the improved dyeing machine and in the form, construction and relative arrangement of its several parts 55 as will be hereinafter more fully described,

illustrated in the accompanying drawings and subsequently incorporated in the subjoined claims.

In the drawing wherein I have disclosed one simple and practical embodiment of my present improvements and in which similar reference characters designate corresponding parts throughout the several views:

Figure 1 is a side elevation of my improved dyeing machine;

Figure 2 is a top plan view thereof;

Figure 3 is a transverse section taken on the line 3—3 of Figure 2; and

Figure 4 is a detail section taken on the line 4—4 of Figure 2.

Referring in detail to the drawing, the dye bath is contained in the usual vat 5 which is of suitable capacity in accordance with the number of skeins to be simultaneously dyed. Upon the upper longitudinal edges of this vat suitable track rails 6 are secured.

A series of transversely positioned shafts 7 are provided upon their opposite ends with the loosely mounted supporting wheels 8 which travel upon the track rails 6. These shafts are adapted to be held in spaced relation to each other by a longitudinally extending bar 9 having spaced notches or recesses 10 in the lower edge thereof to receive the respective shafts. This bar is removably engaged upon the central portions of said shafts and at one of its ends is connected to suitable actuating mechanism to be herein-after described, whereby a unitary reciprocating motion is imparted to said shafts longitudinally of the dye vat.

Upon the inner side of each wheel 8 a pawl or dog 11 is loosely mounted upon a pin 12 fixed in the wheel. The free end of this pawl is adapted for engagement with a radially projecting pin 13 fixed in the shaft 7. A stop pin or stud 14 is also fixed in the inner face of the wheel to limit the outward swinging movement of the pawl 11.

Upon one side wall of the vat 5 and adjacent one end thereof a plate or casting 15 is rigidly mounted, said plate at one of its ends being provided with a suitable bearing for the transversely disposed shaft 16. Upon this shaft the belt wheel 17 is fixed to receive a driving belt extending from the motor or other suitable source of power. Upon the opposite end of the plate 15 the lower end of a vertically disposed lever 18 is pivotally

supported as at 19. A similar lever 20 is also pivotally mounted at its lower end upon a plate or casting 21 fixed to the opposite side of the dye vat. The upper ends of said 5 levers above the vat 5 are connected by a transverse rod 22. The lever 18 is operatively connected with the shaft 16 by any preferred mechanism but for this purpose I have herein shown an eccentric 23 fixed upon 10 said shaft and actuating the arm 24 which is pivotally connected to a link 25, the lower end of which is pivoted as at 26 upon the plate 15. The upper end of this link is connected by means of a second link 27 to the 15 lever 18. A link member 28 loosely engaged at one end upon the central portion of the rod 22 connects said rod and therefore the levers 18 and 20 with one end of the bar 9, said bar being pivotally engaged upon the 20 pin or stud 29 fixed in the end of the link 28.

Upon each of the shafts 7, one or more elongated skein receiving drums 30 are eccentrically secured. Any desired number of these drums may be provided upon each 25 shaft in accordance with the width of the dye vat.

In the operation of the machine as above described, before mounting the shafts 7 in operative position upon the dye vat, the individual skeins of silk or yarn indicated at 30 S, are engaged upon the respective drums 30. The shafts are now disposed in position transversely over the dye vat with the rollers 8 engaged upon the rails 6 and the 35 notched bar 9 is engaged with the said shafts to retain the same in properly spaced relation to each other longitudinally of the vat. The individual skeins S thus depend from the respective drums into the dye bath 40 contained in the vat. Upon operation of the shaft 16, an oscillating motion is imparted to the levers 18 and 20 through the link and eccentric connections, as will be readily understood, and such oscillating 45 movement of the levers is transmitted through the link 28 in the form of reciprocating motion to the bar 9 and the shafts 7. In the movement of these shafts in one direction, the pawls 11 on the wheels 8 engaging the fixed pins or studs 13 in the 50 shafts 7 impart an axial rotation to the individual shafts, thus giving a partial turn to the elongated drums 30. Accordingly it will be apparent from reference to Figure 1 55 of the drawing that in this turning movement of the drums, as the longer axes of the drums are moved from a vertical to a horizontal position with respect to the dye vat, the parallel strands of the individual skeins 60 are separated or spread apart so that the dye liquid may thoroughly permeate all portions of said skein strands. In the reverse longitudinal movement of the bar 9 and shafts 7, said shafts remain stationary while 65 the wheels rotate with relation thereto.

After the dyeing of the skeins is completed, the bar 9 is lifted from engagement with the shafts 7 and said shafts with their supporting wheels 8 then removed from their operative positions upon the dye vat so that the individual skeins can be easily removed from the respective drums 30. In this manner, the thorough and uniform dyeing of the skeins is greatly expedited and the movement of the skeins in the dye bath which is 75 automatically accomplished by means of my present invention, very closely corresponds with the costly laborious hand operation heretofore employed.

In the foregoing description I have particularly referred to an embodiment of my present improvements which is believed to be thoroughly practical. It will be seen that the machine consists of relatively few simply constructed elements which are positive and reliable in their operation, and not liable to get out of order or require frequent repairs. Nevertheless, it will be apparent that substantially the same automatic action might be obtained by means 80 of other alternative constructions and I accordingly reserve the privilege of resorting to all such legitimate changes in the form, proportion and relative arrangement of the several parts as may be fairly embodied 85 within the spirit and scope of the invention 90 as claimed.

I claim:

1. In combination with a dye vat, a shaft 100 transversely positioned above the bath, supporting wheels for said shaft loosely mounted upon the ends thereof, an elongated skein receiving drum eccentrically fixed upon the shaft, means for imparting a bodily reciprocating motion to said shaft longitudinally of the dye vat, and means automatically acting in the initial reciprocation of said shaft in one direction to impart axial rotation thereto and effect a partial 105 turn of said drum to spread or separate the parallel strands of the skein.

2. In combination with a dye vat, a shaft 110 transversely positioned above the bath, supporting wheels for said shaft loosely mounted upon the ends thereof, an elongated skein receiving drum eccentrically fixed upon the shaft, means for imparting a bodily reciprocating motion to said shaft longitudinally of the dye vat, a pawl pivotally mounted upon one of said shaft supporting 115 wheels, and a pin fixed in the shaft and engaged by the free end of said pawl to impart an axial rotation to the shaft in the initial reciprocating movement of the latter in one direction whereby a partial turn is 120 imparted to said drum to separate the parallel strand portions of the skein.

3. In combination with a dye vat, a shaft 125 transversely positioned above the bath, supporting wheels for said shaft loosely 130

mounted thereon, an elongated skein supporting drum mounted on said shaft, means for imparting bodily longitudinal movement to said shaft and drum, and means operated by the wheels when moving in one direction for imparting an axial rotative movement to the shaft and drum with respect to the

dye vat to spread or separate the parallel strands of the skein thereon.

In testimony that I claim the foregoing as my invention, I have signed my name hereunder.

MATILDA NAGLE.
